UNITED STATES PATENT OFFICE.

GEORGE C. KNAUFF, OF CHICAGO, ILLINOIS.

FOCUSING LAMP-SOCKET.

1,173,280.

Specification of Letters Patent. Patented Feb. 29, 1916.

Application filed November 30, 1914. Serial No. 874,752.

To all whom it may concern:

Be it known that I, GEORGE C. KNAUFF, citizen of the United States, residing at Chicago, in the county of Cook and State 5 of Illinois, have invented certain new and useful Improvements in Focusing Lamp-Sockets; and I do hereby declare the following to a full, clear, and exact description of the invention, such as will enable 10 others skilled in the art to which it appertains to make and use the same.

My invention relates to lamp sockets and reflectors and more particularly to means for adjusting the position of a lamp with 15 respect to the reflector associated with the same, so as to bring the lamp filament accurately into the focus of the reflector. In devices of this class, it has been customary heretofore to mount the socket proper slidably with respect to the reflector, and to provide means for maintaining the movable socket portion interlocked at a number of 20 different points spaced longitudinally of the reflector. Such an arrangement is shown, for example, in my copending application No. 856,192 for a patent on focusing sockets, in which the lamp may be interlocked with respect to the socket in any 25 one of a number of positions defined by successive notches or grooves on the casing within which the socket proper may be slid back and forth. In practice, the spacing between successive grooves, when such 30 grooves are made of sufficient depth to afford a firm interlocking, is many times greater than the amount of movement which 35 may be desired for the accurate focusing of the luminous lamp filament. However, unless means are provided for a firm interlocking of the movable socket portion with 40 respect to the reflector, the adjustment will be seriously disarranged by the thrust of inserting a lamp into the socket, this being particularly true when the socket is 45 equipped with the usual spring-pressed contacts which maintain projections on the lamp base interlocked with bayonet catches upon the casing of the socket.

The main object of my invention is to 50 provide a construction which will enable the movable socket portion to be interlocked at innumerable different points with respect to the reflector, and which will readily permit a movement throughout the entire 55 range of adjustment, but which will only

afford a very limited movement upon a sudden thrust such as that involved in the inserting or removing of a lamp from the socket.

Other objects will appear from the following specification and from the accompanying drawings in which—

Figure 1 is a fragmentary view of a reflector equipped with a socket embodying my invention. Fig. 2 is a transverse section 65 through Fig. 1 along the line 2—2. Fig. 3 is an enlarged side elevation of the outer casing of the socket within which the socket proper is slidably mounted. Fig. 4 is an enlarged perspective view of the clamp piece 70 of Figs. 1 and 2. Fig. 5 is a section similar to Fig. 2, showing another embodiment of my invention.

In Fig. 1, the lamp 1 is housed by the reflector 2 equipped with a substantially tubular extension in the form of a shell 3 having a flange 4 whereby the said shell is secured to the inner end of the reflector. Slidably mounted within the shell 3 is a cylindrical tube 5 forming the casing of the 80 socket proper, this casing being equipped at its forward end with bayonet slots 6 engaging lateral projections 7 upon the base of the lamp. Rigidly mounted within the casing 5 is an insulating body 8 carrying 85 wire terminals 9 which are connected by spring-pressed contacts to the terminals of the lamp after the manner well known to those familiar with sockets for automobile lamps. Projecting laterally from the insulating body 8 intermediate to its ends is a shank 10 which extends through the slot 11 disposed longitudinally of the casing 3 and considerably wider than the diameter of the said shank 10. Loosely mounted upon the 95 said shank 10 is a clamp piece 12, preferably curved to conform to the outer surface of the casing 3 and continuously pressed against the latter by a spring 22, the tension of which spring may be adjusted by 100 turning a nut 13 threaded upon the outer end of the shank 10.

It will be evident from Fig. 2 that with the spring-pressed clamp piece 12 bearing against the outer surface of the casing 3 and 105 carried by a shank which extends through the long slot 11 in said shell, the pressure of spring 22 will cause the inner casing 5 of the socket to be drawn firmly against the portion of the shell 3 adjacent to said clamp. 110

Consequently, the movable socket and the lamp carried thereby will readily be maintained at any desired position within the range of adjustment afforded by the movement of the shank 10 within the slot 11. However, it will also be evident that any considerable thrust upon the lamp in a direction longitudinal of the axis of the socket will alter this adjustment and might easily slide the socket portion to one or the other extreme position. To avoid such an action, I equip the clamp piece 12 and the shell 3 with auxiliary interlocking means which will restrict such a relative movement in a direction purely longitudinal of the socket to a quite small distance, but which will permit a longer movement upon a special manipulation of the movable socket portion with respect to the reflector. For this purpose, I preferably equip the casing 3 with a zigzag slot 14 disposed substantially parallel to the slot 11, and equip the clamp piece 12 with a pin or projection 15 extending radially inward of the socket and continuously housed by the said slot 14. The latter slot is preferably made somewhat wider at all points than the diameter of the pin 15 (the latter being indicated in dotted lines in Fig. 3) so that the pin 15 may be moved quite freely within the said slot 14 upon a combined longitudinal and rotationally oscillating movement of the clamp piece 12 with respect to the casing 3, which movement can readily be effected by manually manipulating the bulb of the lamp 1. Consequently, the auxiliary zigzag slot will not interfere with the accurate adjustment of the socket to afford the desired focusing, although the zigzag formation will afford a series of walls spaced longitudinally of the socket and adapted to engage the pin 15 upon a thrust in a direction longitudinal of the socket so as to limit the amount of movement afforded by such a thrust. My construction, therefore, will always limit any possible disarrangement of the adjustment to a quite small amount, after which the needed delicate adjustment can readily be made by manipulating the movable part of the socket.

While I have shown and described my invention as embodied in a form of socket having parallel main and auxiliary slots upon the outer casing and as having a clamp piece carried by a shank and continuously pressed by an adjustable spring, I do not wish to be limited to such details, as it will be obvious that the construction might be modified in many ways without departing from the spirit of my invention. For example, Fig. 5 shows a construction in which the clamp piece 12' slides upon a screw 13' carried by the insulating body 8, which screw projects through the zigzag slot 14 and also carries a curved spring 16 passing around almost the entire circumference of the shell

3. In this case, the slot 11 may be omitted entirely as the entire action will be secured with a single zigzag slot which will afford a series of stops for the screw 13.

I claim as my invention:

1. A focusing socket for a lamp, including as one member a casing, as another member a body carrying said lamp and slidable in said casing: and interfitting means carried respectively by the said members, the portion of said means carried by one of said members affording a series of stops spaced longitudinally of the casing for limiting the relative movement of the said members in a direction longitudinal of the casing member, the said means being releasable from each of their said stops upon a partial rotation of the body with respect to the casing. 70

2. A focusing socket for a lamp, including as one member a casing, as another member a body carrying said lamp and slidable in said casing: clamping means frictionally connecting said members to hold the two interengaged at any point within their said sliding relation: and zigzag means associated with said members for compelling the body to be oscillated about its axis with respect to the casing to afford a longitudinal movement of said body with respect to the casing. 80

3. A focusing socket for a lamp, including a casing, a body member carrying said lamp and slidable in the casing, the casing being equipped with a slot having a plurality of zigzag portions extending substantially longitudinally of the casing: and a projection carried by said body member and extending into said slot, the width of said slot being so proportioned with respect to the size of the projection that the said slot will compel the body member to be oscillated about its axis with respect to the casing in affording a movement of the said body member in a direction substantially longitudinally of the casing. 90

4. A focusing socket for a lamp, including a casing, a body member carrying the lamp and slidable in the casing, means associated with said members for maintaining the same interlocked at any point of their said relative sliding relation, and auxiliary means associated with said members and including interengaging means carried respectively by said members and affording a series of positive stops for interlocking said body member and casing in a number of relative positions spaced substantially longitudinally of the said casing, the said auxiliary means being releasable from each of the said stops upon a partial rotation of the body member with respect to the casing. 100

5. A focusing socket for a lamp, including a casing having a zigzag slot extending substantially longitudinally thereof, a body member slidable in the casing and carrying the lamp, a spring-pressed clamp carried by 110

the body member and engaging the casing to interlock the said body member and casing in an indefinite number of relative positions: and a projection carried by the clamp 5 and disposed in said slot, the zigzag formation of the slot providing a series of wall portions disposed substantially circumferentially of the casing, and said wall portions affording stops spaced longitudinally 10 of the casing to limit the movement of the

body member with respect to the casing by pressure longitudinally of the casing.

In testimony whereof I have signed my name in presence of two subscribing witnesses.

GEORGE C. KNAUFF.
